ATTORNEY.

UNITED STATES PATENT OFFICE.

BENJAMIN E. CANFIELD, OF HOLTON, KANSAS.

CAMPING OUTFIT.

Application filed April 20, 1923. Serial No. 633,493.

To all whom it may concern:

Be it known that I, BENJAMIN E. CANFIELD, a citizen of the United States, residing at Holton, in the county of Jackson and State of Kansas, have invented certain new and useful Improvements in Camping Outfits, of which the following is a specification.

This invention relates to combined tents and beds adapted to be carried on or forming a part of the body portion of a motor driven vehicle, and has for one of its objects to improve the construction and increase the efficiency and utility of devices of this character.

Another object of the invention is to provide a device of this character including a body having outwardly extendable side portions, extensions to the side portions adapted to be disposed vertically relatively to and foldable within the side portions, a fabric canopy, and foldable devices adapted to support said canopy from said side portions and over the extensions of said side portions.

Another object of the invention is to provide a device of this character including a supporting body having means for supporting a fabric canopy and with a swinging rear member adapted to form a table or shelf when in lower position.

With these and other objects in view the invention consists in certain novel features of construction as hereinafter shown and described and then specifically pointed out in the claims, and in the drawings illustrative of the preferred embodiment of the invention:

Figure 1 is a perspective view of the improved device in closed position.

Fig. 2 is a longitudinal sectional elevation with the canopy and its supports in extended position.

Fig. 3 is a transverse section on the line 3-3 of Fig. 2.

Fig. 4 is a detached perspective view of one of the extension frames of the extensible side portions.

Fig. 5 is a detached perspective view of one pair of the brace members of the fabric canopy in collapsed position.

Fig. 6 is a detached perspective view of the ridge member.

Fig. 7 is a perspective detail illustrating the manner of supporting the rear end of the body in horizontal position.

Fig. 8 is an enlarged sectional detail illustrating the manner of holding the frame and canopy top together.

The improved device includes a supporting body in box like form and having a bottom portion 10, side portions 11, top portion 12, and rear portion 13, the latter hingedly connected to the bottom 10 at 14 and thereby adapted to be turned down into longitudinal alinement with the bottom 10 and forming a continuation of the same. Attached to the sides 11 of the body, preferably by staples 15, are combined hangers and strap members 16 jointed at 17 intermediate the ends and with a slot 18 in the free end. The rear member 13 of the body is provided with staples 19 over which the slots 18 of the members 16 engage when the member 13 is closed, and secured in place by a pin 20 or other fastening device. By this means the member 13 may be held in closed position, as shown in Figs. 1 and 2.

Extending from each end of the end member 13 is a staple or similar device 21 with which the slot 18 engages when the member 13 is disposed in horizontal position as shown in Fig. 7, the members 16 thus being utilized to support the member 13 both in closed and open position. The pins 20 or other fastening devices will be engaged interchangeably with the staples 19 and 21, as will be obvious.

A tank 22 for water or other liquid is disposed within the body and provided with a filling cap 23 and draw off valve represented at 24.

Extension side portions are provided, each comprising a longitudinal bottom member 25, a longitudinal side portion 26 rigidly connected at right angles to each other and with oblong end members 27 rigidly connected to the longitudinal members.

The side portions thus constructed are in box like form, as shown.

The members 25 of the side portions are hingedly united at 28 to the upper edges of the side members 11 of the body, so that the side portions may be folded inwardly upon the floor member 12, as shown in Fig. 1, or extended as shown in Figs. 2 and 3, with the members 25 and the floor member 12 in horizontal alinement, as shown in Fig. 3, to form a continuous horizontal floor or bottom to the improved structure.

Mounted to swing upon the side members 11 of the body are bracket devices 29 which fold against the members 11 when the side portions are in closed position, as shown in Fig. 1, and extensible to support the side portions when the side portions are extended, as shown in Fig. 3.

The members 26 and 27 are reinforced at their junctures by corner posts 30, and hingedly united at 31 to the upper ends of the posts are extension members 32, the members 32 at each side being connected by a horizontal rail 33.

Brace rods 34 are swingingly coupled at 35 to the end portions 27, and are formed with terminal hooks 36 to engage staples 37 carried by the members 32.

By this means the extension portions are supported in vertical alignment with the 20 posts 30 and the side members 26 as shown in full lines in Figs. 2, 3, and 4, or permitted to fold into the position shown by dotted lines in Fig. 3.

Hingedly united at 38 to the ends of the 25 members 32, are extension blocks 39, to hold the canopy fabric away from the supporting frame work, the canopy member being indicated as a whole at 40, and of any suitable water proof material, such as tent canvas, and includes a double sided or inverted V-shaped upper portion, and vertical side and end portions.

Coacting foldable end supports or braces are provided, one set of which is illustrated 35 at Fig. 5, and each set comprising longitudinal members 41 and 42 with the confronting faces at one end reversely bevelled and the bevelled faces provided with half sockets 43 and 44, the two members 41 and 42 40 being coupled by pivoted straps 45, so that the members 41 and 42 are free to be disposed in the position shown in Fig. 3, when open, or closed for storage as shown in Fig. 5.

A ridge member 46 extends between the 45 coupled brace members 41 and 42, and is provided with pins 47 at the ends to engage in the half sockets 43 and 44 which unite around the pins when the brace members are distended as in Fig. 3.

At their lower ends the brace members 41 50 and 42 are formed respectively with the notches 48 and 49 to bear over the confronting upper corners of the end members 27, as illustrated at the left in Fig. 3, to support 55 the ridge member 46 in engagement with the canopy fabric.

The notches 48 and 49 are each preferably open at one side, and the open sides covered by metal plates 50 and 51, the closed sides 60 of the notches and the plates 50 and 51 coacting to prevent lateral displacement of the braces.

Hook and staple devices 52 and 53 are attached to the members 27 and the braces 65 41 and 42 to lock the braces to the end mem-

bers 27. Transverse stay rods, one of which is shown at 54, will preferably be applied to the brace members 41 and 42.

The depending ends and sides of the canopy portion will preferably be detachably coupled to the members 26 and 27 by suitable catches, for instance button devices, indicated at 55, or the like, with which buttonholes in the fabric are detachably engaged.

The body portion formed by the members 10, 11 and 12 will preferably be connected in any suitable manner to a motor driven or other vehicle and when being transported or when not in use, the canopy portion 40 will be detached and folded and deposited upon the floor 12 together with the collapsed brace members 41 and 42 and the ridge member 46. The extension members 32 and 39 are then released and folded into the position shown by dotted lines in Fig. 3, and the extension side members are then folded inwardly upon the floor 12 as shown in Fig. 1, thereby enclosing and protecting the portions deposited upon the floor, as above described.

A suitable mattress, not shown, will be employed upon the floor 12.

The end members 27 of the extension side portions are reinforced and strengthened by 95 metal straps 56, as shown in Fig. 1.

The improved device may be constructed of any size or material and readily adapted to any of the forms of motor driven vehicles in use, and requires no change in the vehicle 100 structure, and no material change in the improved device.

The canopy 40 will be held in place by fabric loops, one of which is shown at 57, sewed at one end as represented at 58 to the canopy material where it passes beneath the member 33 and detachably coupled to another part of the canopy as by a button 59.

In packing the bed and mattress are folded on the bottom 12 and the detachable parts 41, 42 and 46 are released from their positions and also placed on the bottom 12. The canopy 40 then drops down over the bed and the sides and ends then folded over the other parts within the body.

The preferred embodiment of the invention is disclosed in the drawings and set forth in the specification, but it will be understood that modifications within the scope of the claimed invention may be made in the construction without departing from the principle of the invention or sacrificing any of its advantages.

Having thus described the invention what is claimed as new is:—

1. A device of the class described comprising a body including a floor member, side portions each comprising longitudinal members at right angles to each other and oblong end members connected to the longitudinal 130

members, one of said longitudinal members of each side portion being hingedly united to the body and said side portions being foldable upon the top member of the body, 5 and means for supporting said side portions in open position.

2. A device of the class described comprising a body including a floor member, side portions each comprising longitudinal members 10 at right angles to each other and oblong end members connected to the longitudinal members, one of said longitudinal members of each side portion being hingedly united to the body and said side portions being foldable upon the top member of the body, 15 and bracket devices swingingly connected to said body and adapted to be disposed beneath said side portions when in open position.

20 3. A device of the class described comprising a body including a floor member, side portions each comprising longitudinal members 25 at right angles to each other and oblong end members connected to the longitudinal members, one of said longitudinal members of each side portion being hingedly united to the body and said side portions being foldable upon the top member of the body, 30 means for supporting said side portions in open position, extension frame devices hingedly connected to said side portions and foldable relative thereto, and means for supporting said frame devices in extended position.

35 4. A device of the class described comprising a body including a floor member, side portions each comprising longitudinal members 40 at right angles to each other and oblong end members connected to the longitudinal members, one of said longitudinal members of each side portion being hingedly united to the body and said side portions being foldable upon the top member of the body, 45 means for supporting said side portions in open position, a canopy support comprising brace members hingedly united at one end and notched at the other ends to engage the confronting corners of the oblong end members of the side portions.

50 5. A device of the class described comprising a body including a floor member, side portions each comprising longitudinal members 55 at right angles to each other and oblong end members connected to the longitudinal members, one of said longitudinal members of each side portion being hingedly united to the body and said side portions being foldable upon the top member of the body, 60 means for supporting said side portions in open position, a canopy support comprising brace members having half sockets in their

confronting faces at one end, coupling straps pivoted to the brace members adjacent the half sockets, said brace members adapted to be engaged with the confronting corners of 65 the oblong end members of the side portions when distended and the half sockets disposed in coactive relation, and a ridge member having pins in the ends to engage in the closed half sockets. 70

6. A device of the class described comprising a body including a floor member, side portions each comprising longitudinal members 75 at right angles to each other and oblong end members connected to the longitudinal members, one of said longitudinal members of each side portion being hingedly united to the body and said side portions being foldable upon the top member of the body, 80 means for supporting said side portions in open position, a canopy support comprising brace members having half sockets in their confronting faces at one end, coupling straps pivoted to the brace members adjacent the half sockets, said brace members adapted to 85 be engaged with the confronting corners of the oblong members of the side portions when distended and the half sockets disposed in coactive relation, tie rods detachably coupled to the brace members when distended, 90 and a ridge member having pins in the ends to engage in the closed half sockets.

7. A device of the class described comprising a body including a floor member, side portions each comprising longitudinal members 95 at right angles to each other and oblong end members connected to the longitudinal members, one of said longitudinal members of each side portion being hingedly united to the body and said side portions being foldable upon the top member of the body, 100 means for supporting said side portions in open position, extension frame devices hingedly connected to said side portions and foldable relative thereto, means for supporting said frame devices in extended position, extension blocks swinging from said extension frame devices to extend the length of the same, a canopy support comprising brace members hingedly united at one end and notched at the other ends to engage the confronting corners of the oblong end members of the side portions, a ridge member supported by said brace members, and a fabric canopy engaging over said ridge member 105 braces and extension frame devices and held in spaced relation to the ends of the body by the extension blocks.

In testimony whereof, I affix my signature hereto.

BENJAMIN E. CANFIELD.
